UNITED STATES PATENT OFFICE.

HERMANN A. KLEMM, OF HARRISON, NEW YORK.

BAG-TYING MACHINE.

1,084,550.

Specification of Letters Patent. Patented Jan. 13, 1914.

Application filed May 26, 1910. Serial No. 569,562.

To all whom it may concern:

Be it known that I, HERMANN A. KLEMM, a citizen of the United States, residing in Harrison, county of Westchester, State of New York, have invented certain new and useful Improvements in Bag-Tying Machines, of which the following is a specification.

This invention has reference to bag tying machines of the kind described in my application for Letters Patent No. 556,375, filed April 19, 1910, and relates particularly to the improvements in the knotting device and its allied mechanisms.

15 It contemplates the use of a hooked latch needle for engaging the leading end of the tying twine and passing it inside of the loops of twine wrapped around the neck of a bag or between said loops and the neck of 20 the bag.

It also includes modifications and other novel features in the construction and arrangement of some of the operative parts of the machines, as shown in the accompanying drawings and hereafter fully described.

Figure 1 is a plan view of the machine embodying the present improvements, with the upper part removed. Fig. 2 is a right-hand side elevation with the vertical shaft 30 and twine carrier in section. Fig. 3 is a plan view of the upper gears shown in Fig. 2, taken on the line 3, 3 Fig. 2. Fig. 4 is a modification in the twine holding reel. Fig. 5 is a side view of the latch needle constituting the knotting device, detached. Fig. 6 shows, in plan, the primary crushing or 35 creasing device. Fig. 7 is a front elevation of all of the creasing devices and bag neck holding devices. Fig. 8 is a side elevation 40 of the parts shown in Fig. 7. Fig. 9 is a horizontal section of the bag mouth holding jaws taken on the line 9, 9, Fig. 2. Fig. 10 is a vertical section of the same, on the line 10, 10, Fig. 9. Fig. 11 is a horizontal section 45 of the upper preliminary neck creasers, taken on the line 11, 11, Fig. 7. Fig. 12 is a plan of the latch needle, its operating mechanism and twine controlling device, on an enlarged scale. Fig. 13 is a side elevation 50 of the same. Figs. 14, 15, 16 and 17 illustrate various stages in the process of securing the knot by a hooked latch needle, showing a side view of the neck of a bag, and Figs. 18, 19, 20 and 21 are rear views of 55 Figs. 14, 15, 16 and 17 respectively.

The machine in its general features of

construction and the operating devices acting on a bag to crease the neck and close the mouth and actuate the other parts of the machine is similar in all essentials to the machine of my before mentioned application and corresponding parts are in the drawings of this case similarly indicated, and it will only be necessary to briefly describe the same to impart a proper understanding of the novel features of this invention, the driving gear, &c., being here omitted.

The preliminary neck creasing and gathering jaws 62, 63 are closed onto the lower part of the neck of the bag as it passes between them into tying position; the jaw 62 is carried by the sliding rods 64, and has an opening through it in line with a slot formed in the bed of the machine for the passage of the new form of knotting needle 111 and its carrying lever hereafter described, and at the end of this slot is placed a thin guard plate 112 to prevent the neck of the bag entering the slot and to hold it away from the needle. The other jaw 63 rocks on the vertically arranged pivot 65 and the neck pusher 67 is rocked on the stud 68 by the operating lever 87 pivoted at 88 and connected to an arm of the pusher 67 by a link 86. The other preliminary neck creasers which act on the upper part of the neck to close the mouth of the bag are carried on the ends of the curved arms 100 pivoted at 101 to the standard *q*; said arms being by 90 the short links 102 operated and controlled by the lever 103 having a pivotal connection 104 on the standard and having a universal connection 105 at its other end with the upper end of the operating rod 106. The closing jaws 113 of this preliminary creaser are angularly formed and secured to the lower ends of the arms 100, as shown at Fig. 11, and their ends or edges 114 interlock. This construction of the jaws insures a perfect 100 action on the mouth of a bag, whether made of a fabric or paper, to properly crease and close the same ready for the action thereon of the device for holding the mouth closed while the tying twine is being applied 105 to the neck. The jaws 115 of the bag mouth holder are similar in construction to the jaws 113 and have interlocking flaring edges 116; they are carried by arms 2 pivoted at 3 to a collar on the lower end of the vertical 110 hollow shaft *y*, and by the links 4 are connected to the arms 5 of a sleeve 6 fitted to

slide on the shaft *y* and controlled by a lever 7, pivoted at 8 to a bracket from the standard *g* and actuated by a cam *d* on the main shaft *a* held in bearings, *h*, *h*, of the machine. The 5 inner face of one of the jaws 115 is provided with a cam shaped piece 117 whose function is to depress the neck of the bag above the knotting needle 111 as the jaws rotate around the neck to insure the proper arrangement 10 of the twine in relation to the needle and prevent interference of the neck with the needle, as shown at Fig. 10. The rotating twine carrier 10 is on the same arm 2 which carries the jaw 115 having the cam piece 117. 15 Power applied to the bevel wheel *x* from any suitable motor imparts intermittent motion to the main shaft *a* through the shaft *p*, bevel wheels *o*, *n*, shaft *h*, and the connecting gears *j* and *i*. The shaft *p* also, by the 20 pair of gear wheels *z*, imparts rotation to the hollow shaft *y*. While this twine carrying shaft *y* is hollow, as in the before mentioned case, the twine does not pass through and in contact with it but through a stationary tube 118 concentric with the shaft and which is rigidly held in a bracket 119 extending from the top of the standard *g*, and the twine holder, here shown as a frame 25 holding a twine reel 121, is secured to a gear wheel 122 fitted on the upper end of the stationary tube 118. It is caused to rotate in conformity with the bag mouth holder and twine carrier 10 by a pinion 123 on a shaft 124 having a bearing in the bracket 125, and a pinion 126 also on the 30 shaft 124 is arranged to mesh with one of the gear wheels *z*.

A modification in the twine reel carrying frame is shown at Fig. 4, having for its object to permit the twine to run more freely off the reel and down the tube 118 the frame 120 being made considerably wider to provide room for the reel 121 to slide along its supporting spindle 127 as the twine is 45 drawn off it down the stationary tube 118, as shown by the dotted lines. By this construction the twine rubs on all parts of the lower edge of the tube while in former machines it rubs over one part only of the hollow shaft *y* tending to cut a groove in its lower edge.

The twine 11 as it leaves the lower end of the stationary tube 118 passes between the guide fingers 16, which are secured to the 50 lower end of the hollow shaft *y* and then passes around a small pulley and down through the eye of carrier 10. Tension is applied to the twine at certain portions of its wrappings around the neck of the bag 55 by a presser 13, pivoted to one of the arms of the bag mouth closer with its gripping face adjacent the side of the arm and which is pressed against and grips the twine by 60 contacting with a stationary cam ledge 15, 65 which is carried by a bracket attached to

the standard *g* and which is arranged in a portion of the path of rotation of the twine carrier 10 to suitably apply tension to the twine as it is wrapped around the neck of the bag. 70

The twine cutter 47 is carried by a slide 48 fitted in a block bearing 49 and is by link 53, bell-crank lever 53, 54, rod 52, and bell-crank lever 51, caused by the cam *e* to advance and cut the twine after completion 75 of the wrapping and about the time of the completion of the tying or knotting of the twine. The guide pin 56 carried on the end of a swinging arm 57 controlled by the cam *m* on the shaft *x* is raised at the proper time 80 to catch and guide the twine for the correct action thereof of the cutter 47.

The gripper which catches the leading end of the twine on the initial movement of the carrier 10 consists of the fixed jaw 17 85 and moving jaw 19 carried at the end of a lever 18 fitted to rock in a vertical direction on a stud 128 held in a block secured to the bed of the machine, and its inner short arm is by the link or rod 129 connected to the lever 30 pivoted at 31 to a bracket extending from the standard *g* and controlled by the cam *e*. The movable jaw 19 is suitably closed and opened by the cam *g* through the medium of the cam roller bearing lever 32 95 pivoted at 27, the rod 34 connecting lever 32 to one end of a lever 35 held on a vertical stud 36, the other end of lever 35 having an arm 37 which by its slotted end embraces a pin 21 extending upwardly from the movable jaw 19. 100

The needle 111 has a hook at its upper end and is provided with a latch 130 adapted to close the entrance to the hook and hold the leading end of the twine in the hook as it is 105 drawn down behind the loops of twine wrapped around the neck of a bag. Before describing the actuating mechanism of the hook and co-operating devices, reference will be had to Figs. 14 to 21 to elucidate the 110 method and procedure of applying and tying twine to and on the necks of bags. The needle with its latch 130 in its downward or open position lies against the neck 69 of the bag so as to be inside of the loops of 115 twine 11 wrapped around the neck by the twine carrier 10 which is laying the last loop as shown at Figs. 14 and 18. The gripping jaws 17 and 19 which hold the leading end of the twine are shown in Fig. 18 as are 120 also shown the twine guide pin 56 and the twine cutter 47. These views represent the first stage of securing the mouth of a bag by twine. The second stage is illustrated in Figs. 15 and 19; here the needle has moved 125 up to bring its latch 130 above the loops of twine, and the grippers 17 and 19 have also been lifted to set the leading end of the twine in position to enter the hooked portion of the needle, the twine being properly 130

held on the end of the lever 18 by means of a notch formed in its upper edge, and to cause the twine to be pressed against the needle to insure its engagement by the hook 5 a pusher 132 is provided, which is controlled and moved horizontally as hereafter described. The guide pin 56 has also been raised at about this time to hold the feeding end of the twine in position to be severed 10 by the cutter 47 when it moves forward. In the next stage or step in the tying process, shown in Figs. 16 and 20, the needle has moved down a sufficient distance for its latch 130 to be raised, by contacting with 15 the top loop of the twine, and to close the mouth of the hook holding the leading end of the twine, the pusher 132 has partly moved back and the grippers 17 and 19 have commenced their downward movement and 20 are about to release the leading end of the twine. The tying is completed as shown in Figs. 17 and 21, the grippers having opened and dropped into their lowermost position, the needle moved down so as to draw the 25 leading end of the twine behind the loops on the neck of the bag with its free end clear of the loops and the cutter 47 moved forward and closed on the feeding end of the twine to sever it a short distance from 30 the twine carrier 10. The needle 111 after tying or knotting the twine continues to move down until its upper end passes below a latch opening device, as a small brush 133 attached to the bed of the machine and so 35 arranged as to act on the latch and move it away from the hook of the needle as the needle is again raised to be in operative position; see Fig. 5. The needle 111 is carried by a lever or swinging arm 134, being 40 by a suitable means, as a nut, secured to its end. This lever is fitted to rock on a stud 135 extending horizontally from a bracket secured to the bed of the machine, and from the hub of this lever projects upwardly a 45 short arm 136, which by an adjustable rod 137 is connected to a lever 138, rocking on the stud 27 and provided with a roller 139 working in the groove of the cam *b* secured to the main shaft *a*.

50 The pusher 132 is formed on or attached to the end of a bar 140, which is fitted to slide in a bracket piece 141 secured to the bed of the machine. A lever 142 pivoted at 143 to the upper end of the bracket piece 55 141 connects to the sliding pusher bar 140 by a slot at its lower end embracing a pin 144 projecting from said bar, and the upper end of this lever 142 is by a link 145 connected to a curved extension of the lever 18, 60 which carries the gripping device, or to an arm 146 secured to said lever 18. This arrangement of parts provides a simple and effective means for actuating the pusher 132, as it operates in conjunction with the twine 65 gripper when it lifts the leading end of the

twine, to push the twine against the needle when in position to be engaged by the hook of the needle.

I claim—

1. In a bag tying machine, means for closing and holding the neck of a bag, means for wrapping a tying twine around the neck, a latch needle having a hook and a hook-closing latch adapted when the latch is open to engage one end of the twine and to draw or pull it while loosely held in the hook when the latch is closed between the closely wrapped loops of the twine and the neck of the bag, and means for operating the needle. 70

2. In a bag tying machine, means for closing and holding the neck of a bag, means for wrapping a tying twine around the neck, a latch needle adapted to draw or pull one end of the twine between the closely wrapped loops of the twine and the neck of the bag, 80 means for passing the needle with its latch in open position behind and beyond the loops of twine and moving it in reverse direction whereby the latch is closed as it passes behind the loops, and means for setting an end of the twine in position for engagement with the needle to be drawn or pulled between the loops of twine and the neck of the bag. 85

3. In a bag tying machine, means for closing and holding the neck of a bag, means for wrapping a tying twine around the neck, a latch needle adapted to draw or pull one end of the twine between the wrapped loops of the twine and the neck of the bag, means for passing the needle with its latch in open position behind and beyond the loops of twine and moving it in reverse direction whereby the latch is closed as it passes behind the loops, means for setting an end of the twine in position for engagement with the needle to be drawn or pulled between the loops of twine and the neck of the bag, 100 and a brush, for setting the latch in open position as the needle again moves into operative 105 position. 110

4. In a bag tying machine, means for closing and holding the neck of a bag, means for wrapping a tying twine around the neck, a tying or knotting needle having a hook at its end and a latch for closing the entrance to the hook, means for setting and holding the needle with its latch open against the neck of the bag to be wrapped with the neck by the twine, means for raising the needle with its latch above the loops of twine and then withdrawing the needle from behind the loops causing the latch to close the entrance to the hook, and means for setting an end of the twine into position to be engaged by the hook and held therein by the latch and thereby placed behind the loops as the needle is withdrawn from the loops. 115 120 125

5. In a bag tying machine, means for closing and holding the neck of a bag, means for 130

- wrapping a tying twine around the neck, a tying or knotting needle having a hook at its end and a latch for closing the entrance to the hook, means for setting and holding the needle with its latch open against the neck of the bag to be wrapped with the neck by the twine, means for raising the needle with its latch above the loops of twine and then withdrawing the needle from behind the loops causing the latch to close the entrance to the hook, means for setting an end of the twine into position to be engaged by the hook and held therein by the latch and thereby placed behind the loops as the needle is withdrawn from the loops, and a brush, for setting the latch in open position as the needle again moves into operative position.

6. In a bag tying machine, a preliminary neck creaser and closer adapted to act on the lower part of the neck of a bag, an upper preliminary closer having angular jaws with flaring interlocking edges adapted to act on the mouth of the bag, a closing and holding device adapted to act on the upper part of the neck or mouth of the bag after the preliminary mouth closer has acted thereon, and means for applying a fastener to the neck between the lower preliminary neck closer and the lower edge of the mouth closer.

7. In a bag tying machine, a preliminary neck creaser and closer adapted to act on the lower part of the neck of a bag, an upper preliminary closer having angular jaws with flaring interlocking edges adapted to act on the mouth of the bag, a closing and holding device having angular jaws with flaring interlocking edges adapted to act on the upper part of the neck or mouth of the bag after the preliminary mouth closer has acted thereon, and means for applying a fastener to the neck between the lower preliminary neck closer and the lower edge of the mouth closer.

8. In a bag tying machine, a preliminary neck creaser and closer adapted to act on the lower part of the neck of a bag, a closing and holding device adapted to act on the upper part of the neck or mouth of the bag, means for applying a fastener, as twine, to the neck between the lower preliminary neck closer and holder and the lower edge of the mouth closer, a hollow rotating shaft vertically arranged above the neck and mouth closers and holders and carrying at its lower end the mouth closer and holder and the means for applying the fastener, a stationary tube extending through the bore of the shaft and down which the fastening twine passes, a twine holder at the upper end of the stationary tube, and means for rotating the twine holder in unison with the rotating shaft.

9. In a bag tying machine, a hollow vertical shaft, a stationary tube in the bore of the shaft, means for holding a bag with its neck in line with the shaft, a closer and holder adapted to act on the upper part of the neck or mouth of the bag, comprising clamping jaws pivotally connected to the lower end of the shaft, a twine carrier also pivotally connected to the shaft and to which the tying twine passes from the bore of the shaft, means for closing the jaws of the neck closer and holder over the mouth of the bag and holding the twine carrier in position to wrap the twine around the neck of the bag, a rotatable twine holder independent of the hollow shaft at the upper end of the stationary tube, and means for rotating the vertical shaft and the twine holder in unison.

10. In a bag tying machine, a hollow vertical shaft, means for holding a bag with its neck in line with the shaft, a tying or knotting needle set against the neck of the bag, a closer and holder adapted to act on the upper part of the neck or mouth of the bag comprising clamping jaws pivotally connected to the lower end of the shaft and having a cam pulse for depressing the neck above the needle, a twine carrier coupled to one of the mouth closing jaws and being thereto also pivotally connected to the shaft and to which the tying twine passes from the bore of the shaft, means for closing the jaws of the neck closer and holder over the mouth of the bag and for setting the twine carrier in position to wrap the twine around the neck of the bag and the needle, and means for rotating the vertical shaft.

11. In a bag tying machine, a twine carrier, means for moving it toward the neck of a bag and means for rotating it around the neck, a gripping device for catching the free or leading end of the twine and holding it as the twine is wrapped around the neck of the bag by the carrier, a hooked latch needle adapted to be set against the neck of the bag to lie behind the wrappings of twine, means for placing the leading end of the twine into the hook of the needle, means for withdrawing the needle from behind the loops of the twine and causing the leading end of the twine to pass between the loops

- of twine and the neck of the bag, and a cutter for severing the twine at its feeding end near the twine carrier after the leading end has been drawn through the loops.
- 5 13. In a bag tying machine, a twine carrier, means for moving it toward the neck of the bag and means for rotating it around the neck, a gripping device for catching the free or leading end of the twine and holding it as the twine is wrapped around the neck of the bag by the carrier, a hooked latch needle adapted to be set against the neck of the bag to lie behind the wrappings of twine, and raised with its latch above the wrapped twine, means for raising the gripper for setting the leading end of the twine to be engaged by the hook of the needle, a pusher for placing the twine in the hook, means for withdrawing the needle from behind the loops of the twine and causing the leading end of the twine to pass between the loops of twine and the neck of the bag. 45
- 10 14. In a bag tying machine, a twine carrier, means for moving it toward the neck of the bag and means for rotating it around the neck, a gripping device for catching the free or leading end of the twine and holding it as the twine is wrapped around the neck of the bag by the carrier, a hooked latch needle adapted to be set against the neck of the bag to lie behind the wrappings of twine, and raised with its latch above the wrapped twine, means for raising the gripper for setting the leading end of the twine to be engaged by the hook of the needle, a pusher for placing the twine in the hook, means for withdrawing the needle from behind the loops of the twine and causing the leading end of the twine to pass between the loops of twine and the neck of the bag. 50
- 15 15. In a bag tying machine, a twine carrier, means for moving it toward the neck of the bag and means for rotating it around the neck, a gripping device for catching the free or leading end of the twine and holding it as the twine is wrapped around the neck of the bag by the carrier, a hooked latch needle adapted to be set against the neck of the bag to lie behind the wrappings of twine and raised with its latch above the wrapped twine, means for raising the gripper for setting the leading end of the twine to be engaged by the hook of the needle, a pusher for placing the twine in the hook, means for withdrawing the needle from behind the loops of the twine and causing the leading end of the twine to pass between the loops of twine and the neck of the bag, the latch of the needle then being closed, and a brush, for opening the latch as the needle commences to move into operative position. 55
- 20 16. In a bag tying machine, a twine carrier, means for moving it toward the neck of the bag and means for rotating it around the neck, a gripping device for catching the free or leading end of the twine and holding it as the twine is wrapped around the neck of the bag by the carrier, a hooked latch needle adapted to be set against the neck of the bag to lie behind the wrappings of twine and raised with its latch above the wrapped twine, means for raising the gripper for setting the leading end of the twine to be engaged by the hook of the needle, a lever for carrying the gripper device and provided with a notch for holding the twine in position in front of the needle, and a pusher for placing the twine in the hook. 60
- 25 17. In testimony whereof, I have hereunto subscribed my name.
